IRONING BOARD

Harry R. Northup, Des Moines, Iowa

Application February 20, 1933. Serial No. 657,630

2 Claims. (Cl. 68—10)

My object is to provide a simple, inexpensive and durable improvement in ironing boards, including a thin metal sheet on top of an ordinary ironing board.

Another object is to so mount the metal sheet that it will be fixed to the ironing board in a manner that will not permit the metal sheet to buckle.

A further purpose is to arrange the metal sheet within the outline of the board, so that it will not buckle against a pad or the like arranged above the metal sheet and secured to the board.

It is my object to provide a sheet of metal which can be quickly heated, which will absorb some but not too much heat, and which will reflect heat, to accomplish the desired results hereinafter referred to.

Another object is to provide such a device with heat insulating material below the reflecting sheet.

Another object is to provide such a board together with a thin cloth covered metal sheet, adapted to be placed over a collar or a part or all of some article to be ironed, in such manner that the user may run the flat iron over the second sheet for ironing the article between the sheets.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a perspective view of an ironing board equipped with a metal sheet and embodying my invention.

Figure 2 is a transverse, sectional view taken on the line 2—2 of Figure 1.

Figure 3 is a vertical sectional view through a second sheet to be attached for ironing collars and the like. In the accompanying drawing, I have used the reference numeral 10 to indicate generally an ordinary wooden ironing board supported by the usual foldable legs 11 and 12, and braces 13.

On the top of the ironing board, I place a thin sheet 14 of heat reflecting metal. The reflecting sheet 14 is of the same general shape in its outline as the board 10, but is shorter and narrower, so that it is placed within the outline of the board 10, and slightly spaced from the edges of the board.

The reflecting sheet 14 is fastened to the board 10 at one end of the sheet 14 as by the bolts 15. The bolts 15 are placed close together, so that the sheet 14 will not buckle between them.

The sheet 14 is arranged within the outline of

the board, so that it will not expand to the edges thereof when heated.

An ordinary cloth pad 16 may be placed over the sheet 14 and fastened to the board 10 in any suitable way.

It will be understood that any means adaptable for the purpose may be used for securing the reflecting sheet 14 to the ironing board 10.

I have found by extensive tests that the ordinary ironing board absorbs a great deal of heat from the flat iron. By using the reflecting sheet 14, experiments show that much of the heat is reflected upwardly instead of being absorbed into the board 10. At first the reflecting sheet 14 absorbs some heat, but at all times, it reflects much of the heat.

By using a reflecting sheet of this kind, I find that the amount of electric current necessary to keep the flat iron hot enough for satisfactory ironing is substantially reduced. Reduction in current amounts to as much as in the neighborhood of 25%. This is true because heat ordinarily absorbed into or passing into the wooden board is reflected upwardly and is not lost where my reflecting sheet is used. Furthermore on account of the fact that the reflecting sheet gets hot and stays hot and reflects much of the heat, I find that the time for the ironing operation is substantially reduced. A damp garment can be ironed much more quickly where a reflecting sheet 14 is employed.

On account of these facts, I also find that better results are obtained in ironing in other respects. For instance, in ironing starched garments, the starch heats much more quickly where the garment receives heat from below as well as from above, and a better gloss is obtained.

Similarly, I find that there is secured with this reflecting sheet a better gloss on ordinary white garments.

The sheet 14 should be quite thin, so it will not absorb too much heat and to reduce expense. The character of the metal and the thickness may be varied to some extent.

Preferably insulating material 19, for instance an asbestos sheet, is placed underneath the reflecting sheet 14. This serves to hold the heat in the reflecting sheet and to prevent passage of heat to the wooden board, and still further contributes to the economy of the electric current. This heat insulating or non-heat conducting material may be in any form and of varying thickness as may be desired, and may be fastened to the wooden board or to the reflecting sheet or may be simply placed in position as an independ-

ent unit. It makes it possible to reduce the thickness of the sheet 14 to a minimum.

The difficulty of ironing some articles, for instance, collars, is well known. I preferably provide for use with my board a thin small sheet A of metal 17, covered by cloth, canvas or the like 18, so as to be quite smooth. I preferably provide the sheet 17 with a flexible handle or the like 19 for convenience in handling it when hot.

10 This sheet A can be placed over a collar or the like, laid out on the ironing board without wrinkles, and the flat iron then run over the sheet A for ironing the collar between the two heated surfaces and assuring the absence of wrinkles.

15 Especially if the sheet A is first heated, this method gives an excellent finish to starched articles.

I claim as my invention:

1. In a structure of the class described, the combination of a supporting element with a thin metal reflecting sheet secured on the supporting element at a limited area only, so that it is free to expand and contract without buckling, and a pad arranged over the sheet and secured to the supporting element.

2. In a structure of the class described, a supporting element, a thin metal heat reflecting sheet on the supporting element wholly within the outline thereof, a pad outside the sheet and extending over the edges thereof and secured to the supporting element.

HARRY R. NORTHUP.
